Primary Examiner — Kevin Rudzinski*Assistant Examiner* — John Reickel(74) *Attorney, Agent, or Firm* — Thomas + Horstemeyer, LLP(57) **CLAIM**

The ornamental design for a electronic device display screen with graphical user interface for a calendar application, as shown and described.

DESCRIPTION

The sole FIGURE is a front view of an electronic device display screen with graphical user interface for a calendar application.

The broken line showing of text and other user interface elements is for the purpose of illustrating portions of the article and forms no part of the claim.
